WIPING CONTACT TYPE SWITCHING APPARATUS

Pentti V. Sarlund, Chicago, Ill., assignor to Zenith Radio Corporation, Chicago, Ill., a corporation of Delaware
Filed Jan. 30, 1962, Ser. No. 169,806
5 Claims. (Cl. 200—164)

This invention relates in general to switching apparatus, and more particularly to a switching arrangement of the wiping-contact type in which a movable switch contact initially wipes a fixed contact before reaching a resting position on that fixed contact.

Wiping action in a switch is desirable since it tends to remove from the switch contacts any foreign material, such as dirt or grease, which would otherwise interfere with the establishment of an electrical connection between such contacts. A wiping connection is customarily made by wiping one contact on another contact in one direction.

While prior wiping-contact techniques are usually effective in providing dirt-free, resistance-less, electrical connections, it is desirable to enhance further the immunity of switch contacts against the deleterious effects of foreign matter that may accumulate on the contacts. This is achieved by the present invention which features a novel bi-directional wiping action wherein a movable contact initially wipes an area of a fixed contact in one direction and subsequently moves backward to wipe the area in the opposite direction.

Accordingly, it is an object of the present invention to provide a novel switching apparatus.

It is another object to provide a switching arrangement which effects bi-directional wiping action of its contacts.

It is a further object to provide a switching arrangement in which the contacts are maintained free of foreign material.

Switching apparatus, constructed in accordance with one aspect of the invention, comprises a first stationary contact assembly having a flat contact surface. A second contact assembly includes a support and a resilient member having one end fixed to said support and having a free end displaced in a given direction from the one end and presenting a second contact surface. Means are provided for pivotally supporting the second assembly for movement in a direction generally the same as the given direction from a first position in which the contact surfaces are out of engagement, through a second position in which the contact surfaces are engaged with the angle defined by the flat contact surface and a line from their point of contact to the one end of the resilient member of less than the critical angle, to a final position. The switching apparatus also includes means for arresting the movement of the free end of the resilient member in the given direction after the second assembly has moved from the second position but before it reaches the final position.

The features of this invention which are believed to be new are set forth with particularity in the appended claims. The invention, together with further objects and advantages thereof, may best be understood, however, by reference to the following description in conjunction with the accompanying drawings, in which identical reference numerals indicate identical elements, and in which FIGURES 1-4 are various views of a switching apparatus embodying the invention.

Before turning to a description of FIGURES 1-4, it should be noted that the switching apparatus to be described is disclosed in copending application Serial No. 169,812, filed concurrently herewith, in the name of George V. Morris. The Morris case illustrates the switching apparatus in the environment of a subscriber communication receiver, specifically a subscription television

2

receiver. The switching apparatus is adjustable and must be adjusted by the subscriber in accordance with a given adjustment before a received intelligence signal may be intelligibly reproduced. The present disclosure only includes that part of the Morris et al. application necessary to illustrate the subject invention. As shown in the Morris case, the switching apparatus is employed to permutably connect a series of input circuits to a series of output circuits in order to permutably apply code signal components to encoding circuitry.

Referring now to FIGURES 1-4, a front plate 230 and a back plate 231 are mounted in parallel, spaced apart relationship with respect to each other by means of rigid spacing and interconnecting structure (not shown). A 15 perforated movable strip or tape 245, preferably made of a polyester material such as Mylar, has its end portions respectively wound around a pair of spools or reels, as fully described in the Morris application. Tape 245 has a series of contact making portions, specifically perforations 247, in a sense randomly positioned on the tape. With the exception of halves 247, tape 245 is very similar to 35 mm. camera film. Regularly spaced sprocket holes, occupying the standard sprocket hole pitch of $\frac{3}{16}$ inch for 20 35 mm. film, are also disposed along both edges of tape 25 245.

Tape 245 also has disposed along one edge thereof, a pre-recorded sound track 244. Preferably, the information pre-recorded on track 244 is simply a continuous sine wave. As fully explained in the concurrently filed 30 Morris case, portions of track 244 are erased by means of an erase head 171 in order to make an internal record of the programs to which a given subscriber has subscribed. The charges registered on track 244 facilitates an audit for each subscriber.

35 The portion of tape 245 intervening that which is wound on the two spools or reels (not shown) is guided through a matrix switch assembly 250 by means of a tape guide 248 and a sprocket 249, each of which has a shaft rotatably mounted in apertures of front and back plates 230 and 231, respectively. The teeth of sprocket 249 extend into the regularly spaced sprocket holes of tape 245, causing rotation of the sprocket as tape 245 is transported or moved. Matrix assembly 250 is rigidly connected to plate 231 and is positioned intermediate tape guide 248 and sprocket 249. Tape 245 is to be moved from one to another of a multiplicity of distinct and spaced positions, and in each such position a different 5×6 matrix or permutation pattern of holes 247 is presented to matrix assembly 250. It has been found that with this arrangement, a length of film 245 of approximately 31 feet may contain at least 2,000 different 5×6 matrix patterns.

40 Matrix assembly 250 includes a framework 252, preferably constructed of plastic. Screws 251 (see FIGURE 1) rigidly mount framework 252 to back plate 231. Viewed from the top, framework 252 is essentially a four-sided, 45 rectangularly shaped open structure composed of the two parallel spaced legs 252a, shown in cross section in FIGURE 2, and the two parallel spaced legs 252b, shown in cross section in FIGURE 3. A series of five shafts or pins 255 are journaled in and mounted between portions 50 252a of framework 252. Rods 255 are mounted in parallel, spaced relationship with respect to each other and also with respect to portions 252b of framework 252.

45 A laterally movable carriage 257 comprises a four-sided, rectangular shaped open structure having two parallel spaced portions or legs 257a, shown in cross section in FIGURE 2, and two spaced, parallel legs or portions 257b, shown in cross section in FIGURE 3. Carriage 257 also has an elongated arm of rectangular cross section extending from the right leg 257b (as viewed in 55 FIGURE 3) in the direction of and through an aperture of front plate 230. As will be seen, arm 256 serves as

a cam-follower. Carriage 257 is interconnected with framework 252 in such a way that carriage 257 is horizontally movable in the direction of parallel legs 257a. This is achieved by providing another series of five parallel spaced rods 258 journaled in and mounted between parallel legs 257a. The carriage is coupled to framework 252 by means of a series of five parallel, rectangular metallic support plates 260 which interconnect rods 255 and 258. Each of plates 260 is electrically conductive and substantially flat except for two end portions which are turned or bent at right angles to provide tabs or flanges 260a to facilitate connections between rods 255 and 258. Flanges 260a are provided with apertures for receiving shafts 255 and 258. In this way, each of plates 260 is pivotably mounted to an assigned one of rods 255 and also to an assigned one of rods 258.

With this construction, framework 252, carriage 257 and plates 260 provide a parallelogram arrangement, like a set of parallel rules; no matter where carriage 257 is positioned it is always parallel to the plane defined by rods 255, and support plates 260 are always parallel to each other. The limit of horizontal travel of carriage 257 is best seen in FIGURE 3. One extreme position of the carriage is shown in that figure in full-line construction. Portion 252c of framework 252 provides a stop for carriage 257. When the carriage is more horizontally to the left in FIGURE 3, it is stopped by portion 252d of framework 252. This extreme position is shown in broken-line construction in FIGURE 3. A pair of coil springs 263 are connected between carriage 257 and framework 252 to urge carriage 257 to the full-line position shown in FIGURE 3.

A cam member 254 (see FIGURE 3), actuated in a manner described in complete detail in the concurrently filed Morris application, engages arm 256 and pushes it, thereby moving carriage 257 to the left against the tension of springs 263 and toward back plate 231. Specifically, cam 254 moves in a direction perpendicular to and up from the view in FIGURE 3.

A series of six separate, parallel spaced, bi-filar resilient spring contact members 265 are mounted to each of the five support plates 260; consequently, there is a total of thirty resilient members 265. Each spring 265 consists of a length of conductive wire having a 180° bend at the middle such that the wire doubles back on itself to form two parallel, bi-filar portions. As viewed in FIGURES 3 and 4, each spring member 265 is of generally L-shaped configuration, the long leg of the L lying against a surface 260b and being mounted at its end portion 265b to an assigned one of plates 260. More specifically, the midpoint of the long leg of the L of each member 265 is loosely retained in a guide 266 formed out of its associated plate 260 and end 265b is rigidly secured by means of a tab 273, also formed out of plate 260, and a solder connection 273a. The short leg of the L, constituting a spring contact 265a, is a free end which protrudes above its associated plate 260; it consists of the two ends of the single wire comprising a spring member 265.

Thus, each of plates 260 provides a support for an associated resilient member 265 which has one end 265b fixed to the support (by means of tabs 273 and connections 273a), an intermediate portion normally lying against a surface 260b of the support, and a free end 265a displaced in a given direction (to the right as viewed in FIGURES 3 and 4) from the intermediate portion and presenting a contact surface.

The portion of tape 254 extending through matrix 250 is disposed immediately above spring contacts 265a. A printed circuit panel 267 lies above both tape 245 and spring contacts 265a and contains a series of six parallel spaced, flat, conductive strips 267a printed thereon on the side immediately adjacent tape 245. Spring contacts 265a and flat contact surfaces 267a are so positioned with respect to each other that a series of five contacts 265a,

one from each of the five plates 260, are disposed below each one of conductive strips 267a. Whether or not one or more of the five contacts 265a associated with each strip 267a establishes an electrical connection with the strip is determined by the matrix permutation of perforations 247 presented to matrix assembly 250 at the time. A metallic plate 269 is positioned immediately above printed circuit panel 267, and it along with panel 267 is mounted to framework 252 by means of screws 271.

10 A series of six input circuits or conductors 51-56 are respectively electrically connected, such as by soldering, to the six parallel conductive strips 267a. A series of five output circuits or conductors 61-65 are respectively electrically connected to the five plates 260, also by soldering. 15 Since plates 260 are constructed of a conductive material and since conductive spring contacts 265a are mechanically and electrically connected to plates 260 by means of tabs 273 and solder connections 273a, output conductors 61-65 are electrically connected to the contacts 20 265a of their associated plates 260.

As mentioned previously, springs 263 urge carriage 257 to the full-line position shown in FIGURE 3. In that position, contacts 265a are spring biased to bear against the underside of perforated tape 245. If an aperture 247 in tape 245 lies immediately above any one of the thirty spring contacts 265a, that contact projects through the aperture to make an electrical contact with the conductive strip 267a lying immediately thereabove. In FIGURE 3 it will be observed that the contact 265a 30 on the extreme right has a hole 247 immediately thereabove and it extends through that aperture to engage a strip 267a. Thus, the pattern of perforations 247 lying below printed circuit panel 267 determines the instantaneous interconnection pattern between input conductors 51-56 and output conductors 61-65.

In order to change the permutation pattern, the tape is moved or transported to a different and spaced position, thereby to present a different pattern of apertures 247 to matrix switch assembly 250. Before tape 247 is moved, however, movable switch contacts 265 are preferably displaced from the tape to avoid possible damage to the tape and contacts. This is realized by actuating apparatus for cam 254, controlled by the subscriber and fully described in the concurrently filed Morris application. Such actuation effects lateral movement of carriage 257 toward back plate 231 (to the left in FIGURE 3) against the bias of springs 263. As carriage 257 is so moved, movable switch contacts 265a retract so that all pressure of the contacts, and in fact physical engagement, is removed from the underside of tape 245. This permits movement of film 245 without interference from the free ends 265a of resilient member 265.

Movement of the tape is accomplished by a mechanism also illustrated in the concurrently filed Morris application. Briefly, driving means are shown in that application for selectively driving either one of the two spools, on which the end portions of tape 245 are wound, in order to move the tape from one position to another in either direction. A single control knob, which is to be rotated by the subscriber, actuates the driving means to permit the subscriber to change the permutation pattern between input conductor 51-56 and output conductors 61-65. Preferably, the manual control knob is to be adjusted differently for each subscription television program so that different permutation patterns are employed for each program.

When tape 245 is moved to a different position by the subscriber, it is desired that apertures 247 line up or register precisely between input contact portions 267a and the associated row of output contacts 265a. Such operation is facilitated by detent means, which positions a star wheel 351 connected to sprocket 249, also described in the concurrently filed Morris application.

A mitre gear 299 is rigidly connected to one end of the shaft of sprocket 249 adjacent front plate 230. An operating shaft 302 controls a cyclometer register (not

shown) and is provided with a mitre gear 303 which meshes with gear 299. Thus, rotation of gear 299, which results from movement of perforated tape 245 in either direction, drives companion gear 303 in order to actuate the cyclometer register. As the cyclometer register is actuated, as is fully explained in the Morris case, different indicia is displayed to the subscriber for each permutation pattern of perforations presented to the input and output switch contacts. In setting up the switching apparatus for a given program, the subscriber must rotate the control knob until a prescribed indicia is displayed by the register.

Turning now to the invention to which the present application is directed, it is to be noted that stationary switch contacts 267a lie above movable contacts 265a. This expedient is employed in order to prevent contamination or fouling of the switching apparatus by settling dust particles. In accordance with the present invention, the contact making arrangement features a unique bi-directional wiping action to insure further that any foreign materials, such as dirt or grease, that may accumulate on flat contact surfaces 267a, or on contacts 265a, are displaced so that nothing interferes with the establishment of the electrical connections.

The invention is best illustrated by the four separate views A-D making up FIGURE 4. Each of the four views shows a single one of elongated, movable resilient members 265 and its associated plate 260 in four different positions. View A shows the retracted position of resilient member 265 when the contact surface of its free end 265a is completely out of engagement with tape 245 and the flat contact surface 267a assigned thereto. The contact surfaces may be so disengaged by moving carriage 257 to the left in FIGURE 3 under the control effect of cam 254. When the cam is subsequently actuated as described in the concurrently filed Morris case (in a perpendicular direction toward the drawing as viewed in FIGURE 3), coil springs 263 cause carriage 257 to move toward front plate 230.

The position in which resilient member 265 finds itself at the instant the contact surface of its free end 265a makes initial contact with its associated stationary flat contact surface 267a through a perforation 247 is shown by View B in FIGURE 4. At that instant, there is a force along line 253, which extends from the anchor end 265b of resilient member 265 to the point of contact of free end 265a and flat contact member 267a, toward surface 267a. In the position shown in View B, the angle defined by flat contact surface 267a and line 253 is within the critical angle. To elucidate, the force along line 253 and toward fixed contact 267a may be resolved into two components—one which is perpendicular to and toward flat contact 267a and another which is parallel to contact surface 267a and extending to the right. The critical angle may be defined as that angle in which the perpendicular force component multiplied by the coefficient of friction of flat contact surface 267a equals the parallel force component. Under such circumstances, resilient spring member 265 would be held in position. However, by making the angle between line 253 and surface 267a less than the critical angle, as in the present invention, the parallel force component is greater than the perpendicular component multiplied by the coefficient of friction, resulting in movement of free end 265a to the right. Thus, as carriage 257 continues to move to the right in FIGURE 3 under the influence of springs 263, shaft 258 moves from the position shown in View B to that shown in View C of FIGURE 4, and during that movement free ends 265a slides or wipes to the right as shown by arrow 259.

To more fully understand the reason that free end 265a moves to the right as shaft 258 moves in the same direction, it is helpful to consider the effect of the stiffness of resilient member 265. Because of that stiffness the triangle formed by member 265 and lines 253 tends to remain unchanged. In other words, the angle between the short leg 265a of the L and the long leg of the L tends to remain constant. As

the contact assembly, comprising support 260 and member 265, pivots about the fulcrum point defined by shaft 255 in moving from the position shown in View B to that shown in View C, stationary contact 267a exerts a force on free end 265a, inasmuch as the anchor end 265b moves closer to contact 267a, tending to compress free end 265a and shorten the line 253 of the triangle. However, due to the stiffness of member 265, line 253 will tend to remain of the same length in going from the position of View 10 B to that of View C and the only way for this to be accomplished is for resilient member 265 to bend or flex away from surface 269b to the right until it bears against shaft 255. Of course, the greatest bending moment will exist at end 265b of spring member 265. Thus, maximum bending takes place at that point.

In the position shown in View C, flexing of resilient member 265 is arrested by shaft 255. Thus, as support plate 260 and pin 258 continue to pivot to the right about shaft 255, free end 265a winds around shaft 255 and thus 20 reverses direction and moves to the left as shown by arrow 262. In other words, shaft 255 serves as a fulcrum point for resilient spring member 265 once the position of View C is attained so that as plate 260 approaches the position shown by View D free end 265a wipes flat contact surface 257a in the reverse direction.

By limiting the travel distance of plate 260 from View 30 C to View D, the contact surface of free end 265a may be arranged to wipe, in the direction of arrow 262, only part of the area of fixed contact 267a previously wiped in the direction of arrow 259. Obviously, such bi-directional wiping action is ideal for establishing an electrical contact. The movable contact first moves over a prescribed area with a wiping action to displace foreign materials that may interfere with proper contact and then 35 moves backward on the wiped surface, reaching a final resting position within the area wiped clean by the first motion. With such an arrangement, the possibility of a faulty electrical connection is virtually eliminated.

By way of summary, the switching apparatus of the 40 present invention comprises a first stationary contact assembly 267, 267a having a flat contact surface 257a. There is a second contact assembly 260, 265 which includes a support 260 and a resilient member 265 having one end 265b fixed to the support and having a free end 265a displaced in a given direction (to the right as viewed 45 in FIGURE 4) from the one end 265b and presenting a second contact surface. Shaft 255 and framework 252, in which the shaft is journaled, may be considered means for pivotally supporting assembly 260, 265 for movement in a direction generally the same as the given direction from a first position (View A) in which the contact surfaces are out of engagement, through a second position (View B) in which the contact surfaces are engaged, with the angle defined by flat contact surface 267a and line 253 from their point of contact to end 265b of resilient 50 member 265 of less than the critical angle, to a third position (View C) with a consequent wiping of the second contact surface on flat contact surface 267a in the given direction (as shown by arrow 259), and thence to a fourth and final position as shown by View D. Shaft 255 constitutes means for arresting the movement of free end 265a of resilient member 265 in the given direction after the second assembly 260, 265 has moved from the second position (View B) but before it reaches the final position 55 (View D). More specifically, arresting means 255 is effective when the second assembly reaches the third position (View C), free end 265a winding around shaft 255 as the second assembly moves from the third to the fourth positions to effect wiping of the contact surface of free end 265a on flat contact surface 267a in a direction opposite from the given direction, as shown by arrow 262.

Certain features described in the present application are disclosed and claimed in copending application Serial No. 117,431, filed June 15, 1961, in the name of Melvin C. 60 Hendrickson et al., and also in the following copending

applications filed concurrently herewith: Serial Nos. 169,766, in the name of George V. Morris et al., and which issued May 19, 1964, as Patent 3,133,986; and 169,792, in the name of Emil C. Walker, now abandoned, all of which are assigned to the present assignee.

While particular embodiments of the invention have been shown and described, modifications may be made, and it is intended in the appended claims to cover all such modifications as may fall within the true spirit and scope of the invention.

I claim:

1. Switching apparatus comprising:

a first stationary contact assembly having a flat contact surface;

a second contact assembly including a support and an elongated resilient member having one end fixed to said support, having an intermediate portion normally lying against a surface of said support, and having a free end displaced in a given direction from said intermediate portion and presenting a second contact surface;

and means including a shaft for pivotally supporting said second assembly for movement about a fulcrum point defined by said shaft in a direction generally the same as said given direction from a first position in which said contact surfaces are out of engagement, through a second position in which said contact surfaces are engaged to a third position, said intermediate portion of said resilient member flexing away from said surface and toward said fulcrum point to effect wiping of said second contact surface on said flat contact surface in said given direction, and thence to a fourth and final position;

said shaft arresting the flexing of said intermediate portion and the movement of said free end when said second assembly reaches said third position, and said free end winding around said shaft as said second assembly moves from said third to said fourth position to effect wiping of said second contact surface on said flat contact surface in a direction opposite from said given direction.

2. Switching apparatus comprising:

a first resilient switch contact;

a second switch contact;

an actuating member to which said resilient contact is mounted;

means mounting said actuating member for motion in a predetermined continuous, unidirectional path, said resilient contact wiping a prescribed area of said second contact in a given direction in response to motion of said actuating member along a first portion of said predetermined path;

and means coupled to said actuating member for causing said resilient contact, in response to continued motion of said actuating member along a second and subsequent portion of said path, to wipe at least a portion of said prescribed area in the reverse direction and to revert to a rest position in electrical contact with said second contact within said prescribed area.

3. Switching apparatus comprising:

a stationary switch contact having a fixed contact surface;

a movable resilient switch contact presenting a movable contact surface;

an actuating member to which said movable switch contact is mounted;

means mounting said actuating member for motion in a predetermined continuous, unidirectional path through a sequence of first, second, third and fourth consecutive positions;

means coupled to said actuating member for holding

5

said contact surfaces out of engagement during the movement of said actuating member from its first to its second positions, said movable contact surface prewiping a prescribed area of said fixed contact surface in a given direction during the movement of said actuating member from its second to its third positions;

and means coupled to said actuating member for causing said movable contact surface to wipe at least a portion of said prescribed area in the reverse direction during the movement of said actuating member from its third to its fourth positions, said movable contact surface thereby coming to rest within the area initially prewiped.

4. Switching apparatus comprising:

a stationary contact assembly having a fixed contact surface;

a movable contact assembly including a resilient spring member presenting a movable contact surface; means for mounting said movable contact assembly for unidirectional movement from a first position in which said contact surfaces are out of engagement, through second and third positions wherein said movable contact surface engages and wipes a prescribed area of said fixed contact surface in a given direction, and thence to a fourth and resting position;

and means operable during the movement of said movable contact assembly from said third to said fourth positions for effecting wiping of said movable contact surface on a portion of said prescribed area of said fixed contact surface in a direction opposite from said given direction, said movable contact surface thereby coming to rest within said prescribed area.

5. Switching apparatus comprising:

a stationary contact assembly having a flat, fixed contact surface;

a movable contact assembly including a support and an elongated resilient spring member having one end secured to said support in cantilever fashion and having a free end angularly displaced from said secured end and presenting a movable contact surface;

means for pivotally mounting said movable contact assembly for movement of said secured end of said spring member about a fulcrum point in a given direction along a path which is generally parallel to said flat contact surface from a first position in which said contact surfaces are out of engagement; through second and third positions wherein said movable contact surface engages and exerts a force toward said flat contact surface, the force having a component parallel to said flat contact surface in said given direction and of a magnitude to effect flexing of said spring member with a consequent wiping of said movable contact surface on a prescribed area of said flat contact surface in said given direction; and thence to a fourth and resting position;

and means for arresting the flexing of said spring member when said secured end reaches said third position and for winding said free end of said spring member about said fulcrum point as said secured end moves from said third to said fourth positions to effect wiping of said movable contact surface on at least a portion of said prescribed area of said flat contact surface in a direction opposite from said given direction.
